ARCHIBALD A. DICKSON, OF TORONTO, CANADA.

MOLDING-MACHINE.

1,099,012.

Specification of Letters Patent.

Patented June 2, 1914.

Application filed September 23, 1911, Serial No. 650,922. Renewed April 1, 1914. Serial No. 828,906.

To all whom it may concern:

Be it known that I, ARCHIBALD BRAKE, of the city of Toronto, in the Province of Ontario, Canada, have invented certain new 5 and useful Improvements in Molding-Machines, of which the following is a specification.

This invention relates to apparatus adapted particularly for molding such articles as cast metal pipes and the like, and my object is to devise a machine which will reduce the hand labor in molding to a minimum and which will produce a clean compactly and evenly rammed mold.

15 I attain my object by means of the construction hereinafter described and illustrated in the accompanying drawings in which—

Figure 1 is a vertical longitudinal section 20 of the apparatus. Fig. 2 is a plan view of the same with the box open. Fig. 3 is a vertical cross-section with a half flask in position on the box. Fig. 4 is a vertical cross-section of a part of the apparatus with the 25 box open and a scraper in place. Fig. 5 is an end view of part of the apparatus. Fig. 6 is a detail partly in side elevation and partly in section illustrating the means for lifting the half pattern. Fig. 7 is a vertical 30 cross-section illustrating the application of power to compress or pack the sand in the half flask.

A is a follower board which is preferably shaped as a hollow rectangular block to 35 guide the vertically movable box B which is formed with sides and ends only. On the follower board is set the pattern, of which only half projects above the surface of the follower.

40 In the drawings a pattern C is shown for a gas or water pipe and for convenience this is turned up as a whole pattern with a core print at each end and projecting half way through a removable plate J which is suitably supported to close the upper side of the hollow rectangular block forming the follower board.

The pattern is supported on two or more connecting rods K which are actuated by the 45 eccentrics L carried by the shaft M journaled longitudinally of the machine preferably provided with a crank handle N. By turning the shaft M the eccentric L may be actuated to push up the rods K and thus the

pattern may be lifted when desired to facilitate its removal from the machine.

The ends of the box B above the level to which the molding sand will be swept is cut away in semi-circular form, as shown, leaving at each end the semi-circular projections 60 D D¹, concentric with the pipe ends. The socket end of the pipe being naturally larger than the spigot end, the semi-circular projection D at the socket end is of greater radius than the projection D¹ at the spigot 65 end in order that the same thickness of sand may surround the socket end as surrounds the spigot end and body of the pipe.

With the device a number of half flasks E are employed. Each half flask in shape approximates interiorly the exterior section of the pipe being molded, allowing, of course, for sufficient thickness of sand.

The apparatus as far as described is used in the following manner: With the parts in 75 the position shown in Figs. 1 and 3 the mold is loosely and evenly filled with sand. The mold is then swept by means of the scraper F shown in Figs. 4 and 5. This scraper is provided with shoulders G to rest on the 80 edges of the box and is shaped at one end approximately the size and shape of one of the semi-circular projections D and at the other end to approximately the size and shape of the semi-circular projection D at 85 the other end of the box. The end of the mold over the socket end of the pipe is swept with the end of the scraper having the curve of larger radius while the rest of the mold is swept by the other end of the scraper. An 90 even thickness of sand is thus obtained over the pattern. A half flask E is then placed in position on the box and locked thereon by means of any suitable removable clamps.

The box and flask are then forced down by 95 hand to the position shown in Fig. 3 and subsequently by power mechanism until the lower edge of the half flask is level with the upper edge of the follower board. The mechanism for moving the box by hand and 100 by power will hereinafter be described. The sand by the actions just described is thoroughly packed in half flask E so that no hand ramming is needed. As the greatest difficulty is experienced in packing the sand 105 around the sides of the pattern I form a shoulder H on the half flask which tends to push down the sand into the space at each

side of the pattern. This sand is further packed by means of a series of wedges I which by means of their pointed ends press the sand longitudinally of the mold where 5 their inner faces being somewhat inclined tend also to pack the sand in toward the pattern. The tight packing of the sand at the parting face of the half flask is of the utmost importance and by means of longitudinal ribs H of the transverse wedges, this is accomplished very effectively. After 10 the last step described the half flask may be removed and a new half mold formed by repeating the process. Two half flasks thus 15 form a complete mold into which the core is inserted and which is poured in the usual manner.

The preliminary downward movement of the box B is given by means of the following mechanism: A transverse shaft O has 20 a hand lever P secured thereto by means of which it may be rocked. This shaft carries the rock arms Q connected respectively by means of the connecting rods a with rock 25 arms R and transverse shafts S journaled transversely at each end of the machine. These shafts S each carry a pair of rock arms T connected by means of pivoted links b with the box B. It is evident that by 30 rocking the lever P the box may be raised and lowered as desired. This hand operating mechanism does not, however, give sufficient power for the final packing of the sand, merely sufficing to bring the half flask 35 down to within one half or five-eighths of an inch of its lowermost position. To enable the power to be applied for the final compression I provide the yoke U which is 40 adapted to engage the top of a half flask when the latter is in position. The top of 45 each half flask is provided with a flat c extending from end to end, as shown particularly in Fig. 1.

The ends of the yoke U are journaled on 45 wrist pins on the crank disks V carried by the shaft W journaled longitudinally of the machine. This shaft carries a gear wheel d meshing with a pinion e on the shaft f which will be driven from any suitable source of 50 power. It will be seen, of course, that some controlling means in the form of a clutch be employed, so that the shaft f may be actuated at such times as may be necessary to raise and lower the yoke U. Such controlling mechanism will be of ordinary construction and forms no part of the present 55 invention.

It will be evident that from the construction described that ample power may be obtained to force the half flask E down to 60 complete the packing of the sand therein which had been commenced by hand.

What I claim as my invention is:—

1. In molding apparatus the combination 65 of a follower board having a $\frac{1}{2}$ pattern

projecting above its upper surface; an open-top box inclosing said follower board and vertically movable relative thereto, the ends of the box having substantially similar vertical contours to the ends of the half pattern but of greater dimensions; and a half flask adapted to be detachably secured to the upper edges of the box, the half flask having its cross sectional contours substantially similar to those of the half pattern. 70

2. In molding apparatus the combination 75 of a follower board; an open-top box inclosing said follower board and vertically movable relative thereto; a half flask adapted to be detachably secured to the upper edges of the box; means for raising and lowering said box; a pivoted yoke adapted to be swung over the top of the half flask when the box is near its lowest position; and means for vertically reciprocating said yoke. 80

3. In molding apparatus the combination 85 of a follower board having a half pattern projecting above its upper surface; an open-top box inclosing said follower board and vertically movable relative thereto, the ends of the box having substantially similar vertical contours to the ends of the half pattern but of greater dimensions; a half flask adapted to be detachably secured to the upper edges of the box, the half flask having its cross sectional contours substantially similar to those of the half pattern; and a series of transverse projections along each 90 side of the interior of the half flask to serve as packers for the molding sand. 95

4. In molding apparatus the combination 100 of a follower board; an open-top box inclosing said follower board and vertically movable relative thereto; a half flask adapted to be detachably secured to the upper edges of the box, and a longitudinal shoulder formed at each side of the half flask above the lower edge thereof and adapted to press the molding sand toward the pattern. 105

5. In molding apparatus the combination 110 of a follower board; an open-top box inclosing said follower board and vertically movable relative thereto; a half flask adapted to be detachably secured to the upper edges of the box, and a longitudinal shoulder formed 115 at each side of the half flask adapted to press the molding sand toward the pattern, and a series of transverse projections along each side of the interior of the half flask to serve as packers for the molding sand. 120

6. In molding apparatus the combination 125 of a follower board having a half pattern projecting above its upper surface and convexly curved in cross section; an open top box inclosing said follower board and vertically movable relative thereto, the ends of the box having substantially similar vertical contours to the ends of the half pattern but of greater dimensions; a half flask adapted to be detachably secured to the upper edges 130

of the box, the half flask having its cross sectional contours substantially similar to those of the half pattern; and a series of transverse projections along each side of the 5 interior of the half flask to serve as packers for the molding sand.

7. In molding apparatus the combination of a follower board having a half pattern projecting above its upper surface and 10 very curved in cross section; an open top box inclosing said follower board and vertically movable relative thereto, the ends of the box having substantially similar vertical contours to the ends of the half pattern but 15 of greater dimensions; a half flask adapted

to be detachably secured to the upper edges of the box, the half flask having its cross sectional contours substantially similar to those of the half pattern; a longitudinal shoulder formed at each side of the half flask adapted 20 to press the molding sand toward the pattern; and a series of transverse projections along each side of the interior of the half flask to serve as packers for the molding sand. 25

Toronto this 16th day of September 1911.
